UNITED STATES PATENT OFFICE.

PHILIP A. JACKSON, OF DAYTON, OHIO, ASSIGNOR TO THE EGRY REGISTER COMPANY,
OF DAYTON, OHIO, A CORPORATION OF OHIO.

AUTOGRAPHIC REGISTER.

Application filed June 5, 1924. Serial No. 717,959.

My invention relates to autographic registers.

It is the object of my invention to provide an autographic register which is capable of winding on a record roll a strip having forms thereon, which forms coincide with similar forms on the strips which are ejected.

It is the object of my invention to provide means of positively feeding all of these strips and of positively winding one of them, consequently maintaining such strips in alignment so that items entered in the forms will be found in the same place in each form.

It is the object of my invention to provide such a combination in which the strip will be held taut to prevent shifting and will at the same time provide a sufficient loop of paper to assist in compensating for the winding of the record roll. It is an additional object to provide in such a combination means to prevent the backward movement of the paper actuating means and winding means for the record roll.

It is an additional object to provide a ready means of loading and unloading the record roll.

Referring to the drawings:

Figure 1 is a section on the line 1—1 of Figure 4.

Figure 2 is an enlarged view similar to Figure 1.

Figure 3 is a perspective of the paper regulator.

Figure 4 is a plan view of the register embodying this invention.

Figure 5 is a side elevation of one side of the record roll support.

Figure 6 is an end elevation of the register guide for the plate.

Figure 7 is a section through a portion of the record roll showing the arrangement of the slipping gear.

It will be understood that to maintain the record roll strip with forms in exact alignment with the forms of the receipt strips, there must be no undue pull on the record strip while it is being fed through the machine due to its being wound on the record roll.

That is the object of the paper regulator, because otherwise the pull of the roll on

which the record strip is wound would accelerate the record roll strip.

55

Referring to the drawings in detail:

1 is a side wall of an autographic register which has a bottom 2 and walls 3 and 4. It is equipped with the usual cover 5, having the cut-out portion 6 to permit 60

writing upon the several strips of paper which are passed over the writing table 7 having carbon sheets interleaved between them. The forward end of the cover is provided with a tear-off edge 8. The front wall is pivoted at 9 and is provided with a lock 10. Spindles 11, 12 and 13 carry the strips 14, 15 and 16 in rolls. These strips are passed over the guide rollers 17, thence on to the writing table, the strips 14 and 15 70

being ejected while the record strip 16 is being conveyed to the record roll 18. All of these strips have marginal perforations which are engaged by the pins 19 of the pinwheel 20. There is a pinwheel on either 75

side of the machine in a conventional manner, the wheels being mounted upon the shaft 21, upon which is also mounted a gear 22. Meshing with this gear is an intermediate gear 23, which is in turn driven by 80

the master gear 24, which is mounted on the shaft 25 carrying the actuating handle 26. A pawl 27 is pivoted at 28 on the inside of the register, which engages with the teeth of the gear 24 to prevent backward movement of the various parts; thus making it impossible for any one to tamper with the machine and prevent the accuracy of its 85

records.

A separate gear similar to 22 is mounted 90 on the shaft 21 on the other side of the machine and drives a gear 29, which in turn actuates a gear 30. 30 drives the gears 31, 32, and record roll gear 33. The record roll gear is adapted to rotate on the supporting 95

shaft 34 upon a predetermined amount of resistance being imparted to the roll 18, so that the strip 16 is always maintained taut, but is not torn, the loop 35 of paper permitting some latitude in this. One end of the shaft 34 is carried on the pivoted bar or lever 36 pivoted at 37 on the wall of the register, the upper surface of the shaft 34 being embraced by the stationary ledge 38. 100

When it is desired to free this shaft, the 105 L-shaped lever 39, which is pivoted at 40

to the register wall, is moved forwardly allowing the supporting lever 36 to drop. This can take place when the door 4 is open.

The other end of the shaft 34, as will be seen in Figure 5, is supported on a pivoted lever 41 which is pivoted at 42 to the register wall. The upper surface of the shaft engages with the fixed shoulder 43. The lever 41 is held in engagement yieldingly against the shaft 34 by the helical spring 44, one end of which is attached to the lever 41 and the other to the register side wall.

The gear 33 turns freely between the plate 45 and the drum 46, upon which the record roll is wound. It is frictionally engaged with the drum and the plate and will not slip except upon a predetermined friction being exerted. A friction plate 47 may be inserted if desired between the plate 45 and the gear 33.

Turning to the specific instrumentality which affects the object of this invention in combination with the rest of the parts, it will be observed that forward of the writing table 7 and somewhat below it is located a plate 48 which slides in the guides 49, carried in either wall of the register. On the bottom of this plate near the outer end there are carried the depending studs 48^a, which engage with the top of the end wall 4 to prevent the withdrawal of the plate when the machine is locked. This plate is provided with projecting fingers 50, which engage with the hooks 51 of the cover to hold the cover down in position. The plate is provided with an upwardly extending portion 52 and a transversely extending portion 53, which overlaps the downwardly and forwardly extending portion 54 of the forward edge of the writing table. Thus the parts 54 and 53 closely overlap, so that the sheet 16 which is drawn between them is closely engaged between their surfaces. This sheet is drawn down tightly over the end of 54 and is thence passed over a broad projecting shoulder 55, carried on a bracket 56, beneath the table 48, thus forming another bearing surface for holding the paper to prevent it being drawn too rapidly by the record roll 50 and therefore accelerated in advance of the superimposed formed strips, portions of which are ejected as receipts or tickets as the registration between the tickets and the record strip must be substantially perfect. As the size of the record roll increases, the clutch will permit of some slipping of the parts.

It will be noted that the paper is closely held and frictionally engaged, so that the pull of the roll does not displace it. It is also conveyed over a zigzag path, which permits of some accumulation of paper in a loop to relieve the strain on the paper and accommodate the fluctuations of the tension on the paper.

I desire to comprehend within my invention such modifications as may be necessary to adapt it to varying conditions.

Having thus fully described my invention, what I claim as new and desire to secure by Letters Patent, is:

1. In an autographic register adapted to contain a record roll strip and one or more receipt strips, one of which is stored as a record, means for maintaining the record roll strip in engagement with the end of a writing table consisting of a plate carrying members attached to its upper and under surfaces, the upper member overlapping the forward end of the writing table and the lower member extending below and rearward of the forward end of the writing table with which the record strip frictionally engages to prevent it from shifting with respect to the other strips. 85

2. In an autographic register adapted to contain a record roll strip and one or more receipt strips, a writing table, a writing cover having a writing opening, pinwheel mechanism for engaging with the margins of the strips, means for actuating said pinwheel mechanism, a record roll, means for actuating said record roll to wind the record strip thereon, a plate having an upwardly and transversely extending portion overlapping the forward edge of the writing table for maintaining the record roll strip closely in engagement with the end of the writing table before it passes to the record roll to prevent the shifting thereof with respect to the other strips, means carried by said plate to frictionally engage a portion of said record roll strip to cooperate in preventing said shifting, and means connected with said plate for engaging with the cover to hold 100 said cover in position. 95

3. In an autographic register adapted to contain a plurality of strips fed from rolls in the register, a writing table, a cover, a plate slidably mounted in the top of said register, means on said plate to pass over the end of the writing table to engage a record strip passing there-between, a shoulder carried by said plate to retard said record strip, and a record roll for winding said strip 115 thereon. 110

4. In an autographic register adapted to contain a plurality of strips fed from rolls in the register, a writing table, a cover, a plate slidably mounted in the top of said register, means on said plate to pass over the end of the writing table to engage a record strip passing there-between, a shoulder carried by said plate to retard said record strip, a record roll for winding said strip thereon, 120 and means carried by said plate for engaging with hooks on the cover to hold the cover in position. 125

5. In an autographic register adapted to contain a plurality of strips fed from rolls 130

in the register, a writing table, a cover, a plate slidably mounted in the top of said register, means on said plate to pass over the end of the writing table to engage a record strip passing there-between, a shoulder carried by said plate to retard said record strip, a record roll for winding said strip thereon, and means carried by said plate for engaging with hooks on the cover to hold the cover in position, said shoulder being placed beneath the end of the writing table so as to draw the record strip against the end of the table.

6. In an autographic register adapted to contain a plurality of strips fed from rolls in the register, a writing table, a cover, a plate slidably mounted in the top of said register, means on said plate to pass over the end of the writing table to engage a record strip passing there-between, a shoulder carried by said plate to retard said record strip, a record roll for winding said strip thereon, means carried by said plate for engaging with hooks on the cover to hold the cover in position, said shoulder being placed beneath the end of the writing table so as to draw the record strip against the end of the table, and means to lock said plate and associated mechanism in position when the end of the register is closed.

7. In an autographic register adapted to contain a plurality of sheets and a writing table, a record roll, means for actuating the sheets and the roll, and a plate having secured thereto an upper and lower member projecting on either side of the end of a writing table for frictionally engaging with the paper of the record strip to prevent the shifting thereof with respect to the other strips.

8. In an autographic register adapted to contain a plurality of sheets, a record roll, means for actuating the sheets and the roll, a plate having secured thereto an upper and lower member projecting on either side of the end of a writing table for frictionally engaging with the paper of the record strip to prevent the shifting thereof with respect to the other strips, and a writing table, said writing table having a portion thereof on substantially the level of the upper of said members, but the end of said writing table passing downwardly and forwardly beneath said upper member and above the lower member.

9. In an autographic register adapted to contain a plurality of sheets, a record roll, means for actuating the sheets and the roll, a plate having secured thereto an upper and lower member projecting on either side of the end of a writing table for frictionally engaging with the paper of the record strip to prevent the shifting thereof with respect to the other strips, and a writing table, said writing table having a portion thereof on

substantially the level of the upper of said members, but the end of said writing table passing downwardly and forwardly beneath said upper member and above the lower member, the end of said writing table projecting beyond the ends of both the upper and lower members.

10. In an autographic register containing a plurality of strips, a record roll and means for actuating said strips to eject a portion of them and to wind one of them on the roll and a plate slidably mounted in the top of said register having upper and lower paper engaging members between which the end of a writing table projects, adapted to frictionally engage said paper of the record strip and to guide it in a zigzag path over the end of the table.

11. In an autographic register containing a plurality of strips, a record roll, means for actuating said strips to eject a portion of them and to wind one of them on the roll, and a plate slidably mounted in the top of said register having upper and lower paper engaging members between which the end of a writing table projects, adapted to frictionally engage said paper of the record strip and to guide it in a zigzag path over the end of the table, said slidably member carrying means to engage with a cover of the register, said cover being adapted to conceal the paper actuating means, said writing table having cutaway portions to receive said paper actuating means.

12. In combination in a paper guide in an autographic register, of a plate, an upper plate-like paper engaging mechanism, of a spaced lower paper engaging shoulder presenting a broad bearing surface, said plate and shoulder being spaced to receive the end of a writing table and fingers located on either side of said plate to engage with a cover of the register to hold it in position.

13. In an autographic register adapted to contain a plurality of sheets of paper fed from rolls in the register, means for actuating said sheets, a plate carrying upper and lower paper engaging members for frictionally engaging with said sheets to prevent the shifting thereof relative to one another, a record roll, means to drive said roll from the paper actuating means, a slipping clutch between said roll and its driving means adapted to slip upon a predetermined tension of the paper being achieved, whereby the record roll strip will be maintained at an even tension and will not be displaced relative to the other strips in order to secure perfect registration, and means for detachably supporting the record roll so that it may be removed without disturbing the rest of the mechanism.

14. In an autographic register adapted to contain a plurality of sheets of paper fed from rolls in the register, means for actuat-

ing said sheets, a plate carrying upper and lower paper engaging members for frictionally engaging with said sheets to prevent the shifting thereof relative to one another, 5 a record roll, means to drive said roll from the paper actuating means, a slipping clutch between said roll and its driving means adapted to slip upon a predetermined tension of the paper being achieved, whereby the record roll strip will be maintained at an even tension and will not be displaced relative to the other strips in order to secure perfect registration, means for detachably supporting the record roll so that it may be removed without disturbing the rest of the 10 15

mechanism, and means for locking the mechanism for supporting the record roll and the paper engaging mechanism.

15. In an autographic register having a plurality of strips, one of which is a record 20 roll strip, pin wheels to feed the strips, a record roll for receiving the record roll strip and a slideable plate having one edge adapted to be moved into said register against said record strip to frictionally engage therewith 25 at a point intermediate the pin wheels and the record roll.

In testimony whereof, I affix my signature.

PHILIP A. JACKSON.
